UNITED STATES PATENT OFFICE

PETE KLIER, OF BISBEE, NORTH DAKOTA

STATIC ELIMINATOR

Application filed September 24, 1929. Serial No. 394,860.

This invention relates to static eliminators for radio receiving sets, and has for one of its objects to provide a device of this character which may be readily connected in the antenna lead, which will function efficiently and which will enable the set in connection with which it is used to be finally tuned.

The invention consists in the construction, combination and arrangement of parts hereinafter fully described and claimed and illustrated in the accompanying drawing wherein:—

Figure 1 is a side elevation of the static eliminator;

Figure 2 is a sectional view on an enlarged scale taken on a plane extending longitudinally and centrally through the static eliminator;

Figure 3 is a sectional view on an enlarged scale taken on the plane indicated by the line 3—3 of Figure 1;

Figure 4 is a similar view taken on the plane indicated by the line 4—4 of Figure 1, and

Fig. 5 is a diagrammatic view illustrating the connection between the coils of the static eliminator.

The static eliminator comprises an outer tube 1 which is made of copper and embodies a lower section 2, an upper section 3, and an intermediate section 4 having its end portions arranged within the upper and lower sections. The lower portion 2a of the section 2 is of conical formation and closed at its lower end, and the upper portion 3a of the section 3 is of conical formation and open at its upper end. The section 2 is provided, near the upper end of its conical portion 2a, with an opening 5 for the reception of a binding screw 6 to which the aerial lead 7 is connected. The sections 2, 3 and 4 are provided with insulating jackets 8, 9 and 10, respectively, which are made of wax paper, and the sections 2 and 3 are provided with insulating jackets 11 and 12, respectively, which surround the insulating jackets 8 and 9 and are made from tape. A closely wound coil 13 is arranged upon the section 4 outwardly of the insulating jacket 10 thereof.

The coil 13 extends from the lower to the upper end of the section 4, and is connected at its lower end to the binding screw 6. The upper end of the coil 13 extends into the section 4 through an opening 14 formed in the section, and is insulated from said section.

An inner tube 15, which is made from brass, is arranged within the tube section 4, and is provided with inner and outer insulating jackets 16 and 17, respectively. A closely wound coil 18 is arranged upon the tube 15 between the insulating jackets 16 and 17 thereof. The lower end of the coil 18 is connected to the upper end of the coil 13 by a lead 19, and the upper end of the coil 18 is soldered within an opening 20 formed in the upper end of the tube 15, as clearly shown in Fig. 5.

A plug 21, which is provided with an insulating jacket 22 made of rubber, has the lower portion thereof arranged within the upper end portion of the tube 15. The upper end of the plug 21 is reduced and closed and provided with an opening 23 in which one end of a lead 24 is soldered. The lead 24 extends through the open upper end of the tube section 3 to the receiving set. The antenna and receiving set being diagrammatically illustrated and designated 25 and 26, respectively. The lower end of the plug 21 is open, and the plug is provided near said end thereof with an opening 27. A conductor 28 is centered at one end within the opening 27, and has its other end soldered to the inner side of the tube 15.

The tube 15 is provided near its lower end with a partition 29 which is made from waxed paper. A bundle of wires 30 have their upper end portions arranged within the tube 15 and below the partition 29, and arranged upon the lower projecting end portions thereof is a cap 31 which is made of brass and has its lower end closed by a plug 32 made of waxed paper. The cap 31 is provided with an insulating jacket 33 made of tape, and an insulating gasket 34 made of rubber is arranged between the adjacent ends of the tube 15 and cap. The cap 31 is provided between the lower end of the wires 30 and

and its plug 32 with a mixture of sawdust and hard oil which is designated 35.

The outer tube 1 and the inner tube 15, together with the intervening insulation 16 and 17, constitute a condenser. The outer coil 13 is a loading coil, and is connected at its lower end to the aerial lead 7 and the outer tube 1 of the condenser. The inner coil 18 is a radio frequency choke coil, has its lower end connected to the upper end of the loading coil 13 by the lead 19, and has its upper end connected to the inner tube 15 of the condenser. This tube of the condenser is connected to the receiving set by the lead 24. The wires 30 constitute a core for the radio frequency choke coil 18, and the cap or receptacle 31, together with the oil saturated sawdust 35 therein and contacting with the core, constitutes means which functions to assist the lagging action of the radio frequency choke coil. This device has been subjected to many tests, and every test demonstrated that it functions to permit the fine tuning of a radio receiving set, and also functions to prevent static from reaching the receiving set. The manner in which the device functions to obtain these ends is not understood by applicant.

While I have described the principle of the invention together with the structure which I now consider the preferred embodiment thereof, it is to be understood that the structure shown is merely illustrative and that such changes may be made, when desired, as fall within the scope of the invention as claimed.

I claim:

1. A static eliminator comprising an inner and an outer tubular member of metallic composition, an inner coil about the inner member, one end of the inner coil being adapted to be connected to a radio receiving set, an outer coil about the outer member, one end of the outer coil being adapted to be connected to an antenna, a shield about the outer coil, and an iron core within the inner member.
2. A static eliminator comprising an inner and an outer tubular member of metallic composition, an inner coil about the inner member, one end of the inner coil being adapted to be connected to a radio receiving set, an outer coil about the outer member, one end of the outer coil being adapted to be connected to an antenna, a shield about the outer coil, and an iron core within the inner member and having a portion thereof extending beyond one end of the inner member.
3. A static eliminator comprising an inner and an outer tubular member of metallic composition, an inner coil about the inner member, one end of the inner coil being adapted to be connected to a radio receiving set, an outer coil about the outer member, one end of the outer coil being adapted to be

connected to an antenna, a shield about the outer coil, and an iron core within the inner member, said core being shorter in length than the inner member and having a portion thereof extending beyond one end of the inner member.

In testimony whereof I hereunto affix my signature.

PETE KLIER.
